CLAIM

The ornamental design for an exercise machine as shown and described.

DESCRIPTION

FIG. 1 is a front, right-side and top perspective view of an exercise machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a right side elevational view of the exercise machine shown in an alternate configuration; and,

FIG. 9. is another right side elevational view of the exercise machine shown in an alternate configuration.

The dashed broken lines in FIG. 7 depict portions of the exercise machine that form no part of the claimed design.

1 Claim, 9 Drawing Sheets
